INVENTOR:
CHRISTIAN J. BEEZHOLD,
by Oscar Hockberg,
his ATTORNEY.

UNITED STATES PATENT OFFICE

2,035,419

CAR CONSTRUCTION

Christian J. Beezhold, Chicago, Ill., assignor, by
mesne assignments, to Pullman-Standard Car
Manufacturing Company, a corporation of
Delaware

Application March 3, 1930, Serial No. 432,940

3 Claims. (Cl. 105—401)

The invention relates to heating systems for railway cars and other vehicles in which the radiators and connecting pipe lines are mounted and concealed within the plane of the wall accomodating them.

Heretofore, the heating equipment for railway cars has involved the use of apparatus disposed within the space intended for the use of passengers, and because of the bulk of such equipment, the occupants of the car have been deprived of sufficient room for their baggage and comfortable disposal of their persons. A further disadvantage resulted from the obstruction to complete door movement and the necessity for cutting away partition and furniture parts to properly fit them to the side wall and projecting pipe housings.

The foregoing and other evils have been overcome by the invention which has for its principal object the concealment of heating coils and pipes within the walls of the car, to the end that the space normally occupied by the passengers shall be free of all protruding heating apparatus.

A further object is to position the heating apparatus in wall recesses and intermediate communicating passages and so dispose the coils and connecting pipes that the surfaces thereof will be exposed to the air of the car interior, and the installation rendered accessible for inspection and repair.

The foregoing and other objects are attained by the construction illustrated in the accompanying drawings, in which

Figure 1 is an inside elevational view of a portion of a car wall having the heating system concealed behind grille wainscoting;

Figure 2 is a horizontal sectional view taken on line 2—2, of Figure 3, showing a radiator installed in the wall between two posts of the car framing;

Figure 3 is a vertical sectional view taken on line 3—3, of Figure 1, showing the mounting of the radiator units and connecting pipe lines, with associated grille wainscoting and framing parts;

Figure 4 is a similar view through the posts separating the radiator units taken on line 4—4, of Figure 1, showing the communicating passages intermediate the radiator recesses;

Figure 5 is a similar view in fragmentary section showing a modified arrangement of the wire conduits to permit upward extension of the radiator recess.

In said drawings, 10 represents a car wall

adapted to receive the heating equipment in accordance with the invention, 11 the windows, and 12 the radiator units of the system. The coils and connecting pipes are positioned between posts 13 of the car framing and between wainscoting grilles 14, 15, and 16, and adjacent girder side 17, as best shown in Figures 2, 3, and 4.

Between the coils 12 and girder sides are deflector plates 18 extending preferably from post to post and from the floor 19 upwardly to a point below the window sills 20. As indicated in the figures, the space between the girder sides and the several deflector plates 18 is lined with insulating material 21 designed to prevent the radiation of heat to the girder side and secured to the girder and deflector plates in any suitable manner.

As shown in Figure 1, the radiators 12 are disposed at spaced intervals along the wall 10 and separated by certain of the framing posts 13 forming recesses 22 extending from the under-frame longitudinals or floor strips 33 to the longitudinal deflector wall portions 23 for the accommodation of the radiator units. The longitudinal deflector wall portions 23 on deflector plates 18 function to direct the air heated by the radiators to the car interior and to connect adjacent posts 13 and wainscoting 14 as best shown in Figure 3.

In the present embodiment, the heated air in the radiator recesses is prevented from entering wall areas beyond associated posts 13 by supplemental post elements 24 filling the space between the several posts 13 and respective wainscoting grilles 14 as shown in Figures 2, 3, and 4, and between the deflector wall portions 23 which are overhanging the radiators and the intermediate longitudinal framing strips 25 traversing recesses 22 and connecting the framing posts 13. The wainscoting grilles 14 are removably held to the post elements 24 by battens 26 fastened by screws 27 to post filler elements 24, by other screws 28 to longitudinal framing strip 25, and by screws 29 to contiguous longitudinal edges of deflector wall portions 23 bordering the margins of the grille openings.

The wainscoting base grilles 15 are secured along their upper margins to the longitudinal framing strips 25 by the screws 28 fastening the lower edges of the relatively higher grilles 14, and at their lower edges to the floor 19 as shown in Figures 3 and 4. To prevent dirt and other matter from entering the radiator space 22 behind the grille 15, the grilles are preferably formed with an imperforate area 31 projecting above the

floor line to a height sufficient to effect that purpose. As indicated in Figure 3, the deflector plates 18 extend to the floor line and terminate in lateral flange portions 32 designed to overlap 5 and be supported upon adjacent floor strips 33 of the underframe 34. Supported upon flanges 32 of the deflector plates are the strap brackets 35 adapted to carry the radiators 12 and secured to the deflector plates by brazing or other means 10 and to which the radiator coils may be attached by screw bolts 36 securing clamping plates 37 best shown in Figures 2 and 3. The brackets 35 are preferably formed to provide seat portions 38 for supporting the coils to relieve the screw bolts 36 of a portion of the weight of the coil as shown 15 in Figure 3.

It will be noted that the deflector plates 18 are extended upwardly beyond the overhanging wall portions 23 to provide wall areas 39 for securing 20 the insulation 21 at that point, thence to the window sills 20 and there secured by screws 40, or the like, as best shown in Figure 3. Thus arranged, space 41 is provided between posts 13 and adjacent wainscoting 14 for the accommodation 25 of wire conduits 42, properly insulated from the underlying heated wall portion 23 of deflector plates 18, and removably attached to the posts by clamps 43 to avoid piercing the posts for the passage of the conduits.

30 In this embodiment, the coils 12 are supplied and drained respectively by pipe lines 44 and 45 communicating with automatic valve regulating devices beneath the car and not here involved. To avoid piercing the posts 13 between the coils, 35 the pipe lines extend outside of the posts and through communicating passageways 46 between the radiator recesses 22. The supply line 44 is offset to connect with the coils in the plane of the posts while the drain line 45 retains a direct 40 course to the regulating valve, both lines being positioned beneath the longitudinal framing strip 25 defining the upper side of the passageways 46 and removably secured to the several posts 13 by clamps 47 held by screws 48 as best shown in 45 Figure 4.

Between the pipe lines 44 and 45 and the posts 13 in passageways 46, deflector plates 49 are adapted to close the space behind the pipe lines in the areas of wainscoting grilles 16 intermediately the base grilles 15, for the purpose of directing air drawn from the car interior to adjoining radiator recesses 22. By the action of the ascending air currents in said recesses the air in the passageways 46 is entrained by the air 55 entering base grilles 15 to provide an air stream supplementing those developed in the recesses 22 by the emission and displacement of the air in the radiator zone. As indicated in Figures 3 and 4, the relatively cool air adjacent the floor line 60 of the car is drawn through the base grilles 15 and 16 and swept across the radiating field of the coils 12 and pipe lines 44 and 45.

The deflector plates 49 are provided with upper and lower attaching flanges 50 and 51 securing the plates to respectively adjacent framing and floor strips 25 and 33. Immediately above the openings in emission grilles 14 the wainscoting is provided with hot air deflecting strips 52 secured thereto by screws 53, or otherwise, to protect the wall areas above them from the ravages 65 of the heat issuing from the grilles.

It may be desirable at times to increase the areas of heat emission grilles 14 by extending the radiator recesses upwardly to the window sills as

shown in Figure 5. In that figure, the wire conduits 142 are in the plane of framing posts 113, pierced to accommodate the conduits, to provide room for the upward extension of the radiator recesses. For this purpose the deflector plates 5 113 are offset at 123, thence upwardly to the window sill 120, to provide wall surfaces for the attachment of insulation 121 for the protection of the conduits 142 from the heat of the radiators 112. 10

As shown in Figure 5 the radiator supporting brackets 135 are detachably secured at their respective upper ends to the window sill by screws 140. As in the case of the post fillers 24 of the preferred embodiment, fillers 124 are provided between wainscoting grilles 114 and adjacent posts 113 to at once prevent dissemination of convected 15 heat to areas beyond the radiator recesses 122 and provide abutments for the grilles secured to them by the battens 126. 20

It will be noted that there has been provided an arrangement in which the car structure and heating apparatus are co-ordinated to eliminate bulky groups of heating coils and their housings from the space between the walls of the car. 25

The full radiating value of the several coils in the present embodiment becomes available convectively by the constant circulation of air across the radiators drawn from and returned to the car interior. The arrangement makes possible a 30 great saving resulting from the elimination of waste due to heat losses by conduction and faulty radiation incident to the use of direct heating apparatus.

With the several upper wainscoting grilles 14 35 removably secured to the wall, and the base grilles 15 and 16 consecutively arranged in the wall and also removably secured, a number of the coils 12 with their connecting supply and drain pipes 44 and 45 may be removed from and mounted within 40 their respective wall niches, as a unit.

What I claim is:

1. In a passenger car, a wall element comprising 45 post members and connecting longitudinals defining recesses spaced apart, passageways in the post areas inwardly of said posts between said recesses and communicating therewith, and wainscoting grilles covering said passageways and recesses.

2. A passenger car comprising upright frame members, an outer car wall secured to said frame members, an inner wall forming with said frame members and said outer wall a plurality of recesses each adapted to receive a radiator, said inner wall being spaced inwardly from said frame members to form passageways between said members and inner wall through which supply and discharge pipes for said radiators may extend. 50

3. A passenger car comprising upright frame members, an outer wall secured to said frame members, an inner wall forming with said frame members and said outer wall a plurality of recesses, each adapted to receive a radiator, a floor for said car, and spacer members between said upright members and said inner wall spacing said inner wall inwardly from said upright frame members and forming passages between said recesses both above and below said spacer members, through which wire conduits and supply and discharge pipes for said radiators, respectively, may extend. 60

CHRISTIAN J. BEEZHOLD.
